Wm H. Reid.

UNITED STATES PATENT OFFICE.

AUGUST WILLENBACHER, OF HACKENSACK, NEW JERSEY, ASSIGNOR TO TRIUMPH MANUFACTURING CO., OF NEW YORK, N. Y., A FIRM.

LAMP-SHADE HOLDER.

Application filed May 1, 1925. Serial No. 27,143.

To all whom it may concern:

Be it known that I, AUGUST WILLENBACHER, a citizen of the United States, and a resident of Hackensack, in the county of 5 Bergen and State of New Jersey, have invented new and useful Improvements in Lamp-Shade Holders, of which the following is a specification.

This invention relates to lamp shade holders, that serve to mount an electric lamp, and also its shade on any suitable or convenient base or support.

The object of the present invention is to provide means for clamping the usual lamp 15 socket by its threaded attachment, to a rod frame, through suitable clamping members that are pressed together to enclose and clamp the rod at its base portion.

In the accompanying drawing showing 20 embodiments of my invention, Figure 1 is a side elevation, of the device partly in section.

Fig. 2 is a bottom plan view partly in section.

Fig. 3 is a top view of the cup member.

Fig. 4 shows the cup member in section.

Fig. 5 shows the washer.

Fig. 6 shows the locking member.

Fig. 7 shows a modified form.

One object of the present invention is to provide means for securing the device of this character formed of a bent rod, for securing the lamp socket to the rod by means of a pair of members that are clamped together on the rod by means which are used to secure the lamp or the shade to the holder.

The device as shown comprises two members, a cup member and a washer. The holder as set forth comprises a rod having side portions 2 and 3 connected by an integral bottom or transverse portion 4, that is given a curve or bend 5 at the middle portion. The upper end of the side bars 2 and 3 are brought together and suitably secured 45 to a head 6. As set forth the ends are deflected at 7 and 8 and are embedded in the head 6 by having the head cast around them. This head also carries a threaded stud 9 whose head is embedded in the casting, that 50 can serve to secure the shade or shade carrier. But the device as set forth does not form subject matter of the present application.

The usual electric lamp 10 has its base 55 provided with a sleeve 12 internally thread-

ed to receive a threaded sleeve 13, see Fig. 6. The latter is provided with a flange 16 that is employed to secure the lamp socket to any suitable member or device. These parts are standard in the trade.

This invention provides means whereby the bent rod at its lower portion 5 can be clamped between the lamp and the flange 16 of the sleeve 15. I provide a cup member 17 having a base 18 with a central opening 19 of a size to permit free entrance of the sleeve 15. At opposite sides of the cup flange it is cut away at 20, 21, to admit the transverse portion 4 of the supporting rod. The cup is of a size to receive the curved portion 5 of the rod, the ends of which enter the sockets 20 and 21, see Fig. 2, which will permit the curved portion to rest on the annular bottom 18 of the cup member, as shown. A washer 22 is provided of a size to enter the cup portion and the side wall of the cup flange is of a height to have the washer rest on the top of the curved portion 5, with its edge engaging the side walls. The washer is preferably somewhat tapered and will have a tight fit in the cup, so that it can be forced down and retain the cup engaging the curved part 5 of the rod. This will permit a ready assembly of the parts, and they can be packed and stored in this form. When ready for use the sleeve member 15 is passed up through the cup and washer, and screwed into the threaded sleeve extension 12 of the lamp socket, until the flange 16 engages the bottom wall of the cup, and forces it upward, bringing the washer 22 against the lower edge of the socket sleeve 12, as shown in Fig. 1. This will serve to tightly clamp the cup member and washer in engagement with the curved portion 5 of the rod and hence the lamp socket is securely locked to the rod member.

What I claim is:

1. A lamp support comprising a rod bent to form a transverse lower portion with 100 arms projecting upwardly that are brought together at the top, means rigidly connecting said ends and forming a shade support, said transverse base portion being deflected laterally at its middle portion to form a semi-circle, a pair of annular clamping members engaging said deflected portion, and means for holding them together engaging said deflected portion, comprising a 105 threaded sleeve having a flange, which sleeve 110

- can pass through the annular members into the threaded sleeve end of a lamp socket, whereby to clamp said members together against the rod portion and support the rod.
- 5 2. A lamp support comprising a rod bent to form a transverse lower portion with arms projecting upwardly that are brought together at the top, means rigidly connecting said ends and forming a shade support,
- 10 said transverse base portion being deflected laterally at its middle portion, to form a semi-circle, a pair of annular clamping members engaging said deflected portion, said members comprising a cup portion having opposed openings in the side walls through which the rod passes with its deflect-
- ed portion extending around the bore of said members, and a washer fitting into the cup member to clamp the deflected portion between it and the base of the cup member, and
- 20 means for holding them together engaging said deflected portion, comprising a threaded sleeve having a flange which sleeve passes through the annular members into the threaded sleeve end of a lamp socket, whereby to clamp said members together against the rod deflected portion and support the rod.
- 25

Signed at New York city, N. Y., April, 1925.

AUGUST WILLENBACHER.
